CUTTING MECHANISM FOR AXMINSTER LOOMS

Filed Dec. 26, 1941

FIG. 1

UNITED STATES PATENT OFFICE

2,306,304

CUTTING MECHANISM FOR AXMINSTER LOOMS

Edward J. Dacey, Worcester, Mass., assignor to
Crompton & Knowles Loom Works, Worcester,
Mass., a corporation of Massachusetts

Application December 26, 1941, Serial No. 424,458

5 Claims. (Cl. 139—2)

This invention relates to improvements in Axminster looms and it is the general object of the invention to employ a tuft yarn cutting mechanism so constructed as to prevent an accumulation of lint in certain parts of the loom.

Axminster looms operate with a series of tube frames which are presented one at a time to tuft forming position. The yarns are projected through the warp shed and are then bent up and rearwardly to form tufts, after which cutting mechanism severs the tufts from the yarns carried by the tube frame. In a type of Axminster loom which has gone into common use it is customary to employ a notched or toothed cloth or nose board which assists in the formation of tufts. This board comprises a plate from the rear edge of which project vertical teeth separated by slots into which move the dents of the reed and also guide plates which cooperate with the reed dents to form guide aisles for the tuft yarns when the latter are being bent to form the tufts.

As heretofore constructed the cutting mechanism on such looms has comprised front and back blades which are normally separated during the tuft forming operation but which move toward the tube frame during the cutting operation. It is usual to move the front or ledger knife rearwardly to a position close to the tuft yarns and hold it stationary in that position while the rear knife is moved forwardly and under the front knife to cut the row of tufts from the tube frame. During the cutting operation considerable lint is formed which has a tendency to fall into the slots between the teeth of the nose board and interfere with the operation of the reed dents and guide plates. While the rear knife moves forwardly the short ends of the yarn and other lint fall on it and is carried rearwardly as the knife recedes. After the knife has reached a position behind the teeth of the nose board and the fell of the cloth the lint on the back knife falls off onto the nose board teeth and the shed from which positions it is carried into the slots by the reed when advancing. Because of the construction of the loom it is desirable to have the back or cutting knife move under the front knife and it is for this reason that the lint accumulates on the cutting knife.

It is an important object of my present invention to reverse the operation of the cutting blades and move the rear blade forwardly to a temporarily stationary position after which the front knife moves toward and under the rear knife to cut the tufts and the yarns extending

from the tube frame. The cutting occurs over the fell of the cloth and slightly in front of the exposed part of the teeth behind the fabric, but after cutting the lint which accumulates on the 5 knife moves forwardly with the latter and in falling off the front knife is deposited on the cloth a considerable distance in front of the teeth of the nose board and the binders of the warp shed. In this way the lint released during the cutting operation is kept away from the slots through which the reed dents and guide plates move.

Prior to cutting the yarns which project from the tube frame extend downwardly and are then curved rearwardly and upwardly to present a short strand on the rear part of the tuft. When a front knife is used the rearwardly directed cutting force has a tendency to bend the rear strand of the tufts out of cutting position, resulting in the formation of rows the pile tufts of which are of uneven height. It is a further object of my present invention to provide the teeth of the nose board with upstanding hooks along which the rear strands of the tufts extend for support during the cutting operation. The hooks on the cloth board project upwardly toward the rear temporarily stationary knife and prevent the rear strands of the tufts from moving out of cutting position.

With these and other objects in view which will appear as the description proceeds, my invention resides in the combination and arrangement of parts hereinafter described and set forth.

In the accompanying drawing, wherein a convenient embodiment of my invention is set forth, Fig. 1 is a vertical section through part of an Axminster loom having my invention applied thereto with the cutters separated and the tube frame in tuft forming position,

Fig. 2 is a detailed elevation on an enlarged scale of a portion of Fig. 1, showing the tuft bent to cutting position and the back or ledger knife in its temporarily advanced stationary position,

Fig. 3 is a view similar to Fig. 2 but showing the front knife passing under the rear knife to cut the tufts from the tube frame, and

Fig. 4 is a view similar to Fig. 2 but showing the relationship of the parts as the front knife 50 moves forwardly.

Referring to the drawing, the loom frame 10 supports a lay shaft 11 on which is mounted a reed R between the dents of which the binder warps forming the top and bottom sheds W and W' respectively, extend to the woven fabric. By

means of a connector 12 the lay is advanced to move the reed forwardly or to the left as viewed in Fig. 1 every beat of the loom. A weft laying needle N is projected into the warp shed when the reed is in rear position to insert a double pick of filling and is then retracted to permit beat-up of the reed.

A bracket 15 secured to the loom frame supports a cloth board 16 having a plate or body 17 from the rear edge of which projects a series of vertical teeth 18. These teeth are separated by slots 19 and are each formed with a rear curved surface 20 which cooperates with the yarn Y projecting from the tube frame T to form tufts as the reed advances and moves into the slots 19.

A carriage 25 having pivotal support as at 26 has mounted thereon a series of guide plates 27 which align with the reed dents and are normally located in front of the teeth 18. By means of a rod 28 the plates 27 are moved rearwardly on each tuft forming operation of the loom to define guide aisles with the reed dents, after which said plates move forwardly with the reed.

The tube frame may be mounted on customary transfer arms 30 by means of which it is detached from the tube frame, moved to the tuft forming position shown in Fig. 1, raised preparatory to cutting, and then returned to the chains. While the tube frame is in tuft forming position it is given the customary rolling-in movements which assist in the forming of tufts. At the end of the tuft forming operation the yarn Y has the shape shown in Fig. 2 with a rear short upright strand S.

In the operation of the mechanism thus far described the tube frame will be dipped and the plates 27 moved rearwardly for each tuft forming operation and the reed and plate 27 will move forwardly so that the yarns Y will be guided up the curved surfaces 20 and over hooks 33 formed on the teeth 18 and projecting above the top surface 34 of the plate 16 on which the woven fabric rests. The construction set forth may be of the usual construction and for a further understanding of the structure and operation thereof reference may be had to prior Patent No. 1,958,129.

As heretofore stated it has been customary to cut the tuft from the yarns Y by means of front and back cutters the rear of which moves under the temporarily stationary front knife during the cutting operation. In my present invention I reverse this operation and provide for mounting the cutting blade in front of the tufts. In Fig. 1 I have shown one convenient means for supporting and operating the front knife including a bracket 40 bolted to the loom frame and having mounted thereon a guide block 41 provided with a downwardly and rearwardly inclined guide slot 42. Positioning screws 43 are used to determine the vertical position of the block 41 with respect to the bracket 40 and bolts 44 hold the block 41 to the bracket 40. A relatively large knife bar 47 of angular section as shown at the left hand part of Fig. 1 has a shoe 48 to extend into and be guided by slot 42. The lower end of the bar is connected as by a head 49 to a link 50 the rear end of which is connected to an operating lever 51. The latter is mounted on a heavy shaft 52 and is connected to the rod 53 extending to suitable mechanism for the purpose of reciprocating the bar 47 with respect to the guide block 41.

Secured to the under side of the bar 47 is

the front knife 55 held to the bar by bolts 56 and having a projecting rear cutting edge 57. Under normal conditions the lever 51 is in its left hand or forward position with the cutting edge 57 spaced forwardly from and out of interfering position with respect to the tube frame when the latter is in tuft forming position.

Similar mechanism for the rear or ledger knife comprises a bracket 60 secured to the loom frame 10 and having a guide block 61 secured thereto by bolts 62 and vertically adjustable thereon by bolts 63. The rear knife bar 64 is of angle section and is connected by means of a rod head 65 to a rearwardly extending rod 66 attached to the upper end of an operating lever 67. The bar 64 is provided with a shoe 68 which fits into a guide slot 69 formed in the block 61. Secured to the under forward side of the bar 64 is a cutter or ledger blade 75 held to the bar by bolts 76. The ledger blade has a front cutting edge 77 to cooperate with the rear edge 57 of the front knife.

Under normal conditions the knives are separated as shown in Fig. 1 but after the tube frame 25 has had its tuft forming motions and the tuft 30 is of the shape shown in Fig. 2, lever 67 will be moved forwardly to cause the bar 64 to advance until the cutting edge 77 of the rear knife lies close to the yarn Y over the hooks 33. Motion 35 of lever 67 is then arrested and the back knife 30 is held in this position. Thereafter, lever 51 moves rearwardly, or to the right as viewed in Fig. 1, to move the front bar 47 backwardly to cause cutting cooperation between the two 40 blades. The front knife advances from the position shown in Fig. 2 to that shown in Fig. 3 while the rear knife 75 is held stationary and the cutting edge 57 of the movable front knife moves to a position to the right of, or behind, 45 the edge 77 of the ledger blade. The tufts are thus cut from the yarn Y and in the cutting operation any lint or the like which is released falls on the top of the front knife as indicated at L. It will be noted in Fig. 3 that the cutting 50 occurs substantially over the fell of the cloth and that the cloth extends forwardly from this point covering those portions of the slots 19 under it.

After the cutting operation is completed the 55 front knife is moved forwardly from its full line position shown in Fig. 4 to the dotted line thereof and the lint is carried forwardly by the front knife to a position in front of the fell of the cloth and over the woven fabric. If the lint 60 should fall from the cutter blade 55 or be purposely dislodged by the operator it will fall onto the cloth and will not fall into the slots 19.

It will be noted that during the cutting operation the hooks 33 extend upwardly along and 65 behind the rear strands S of the tufts being formed to support and hold them in position for cutting. This is particularly noticeable in Fig. 3 where it will be seen that the rearward force exerted on the tuft by the front knife during the cutting operation is resisted by the hooks 33. After the cutting knife 55 has started to move forwardly the rear knife 75 will move backwardly and when the cutting operation is completed the knives will again be in the position shown 70 in Fig. 1.

While I have described the mechanism located at one side of the loom it is to be understood that the blocks 41 and 61 and the parts 75 associated with them are duplicated on the op-

posite end and that the bars 47 and 64 slide along slots at each side of the loom.

From the foregoing it will be seen that I have provided cutting mechanism for an Axminster loom employing two knives the rear one of which is held stationary during cutting operation and the forward one of which is moved to effect the cutting and passes under the rear knife so that any accumulation of lint released incidental to cutting falls on the front knife. Thereafter, as the front knife moves forwardly to its normal position, the lint will be carried with it and if dislodged will fall on the fabric and not on the teeth of the nose board or into the slots 19. By this operation the slots are kept free of lint and the reed dents and guide plates 27 operate without interference on the part of lint. It will also be seen that the upright hooks 33 on the teeth of the nose board extend upwardly along the rear strands S of the tufts being cut and support the latter during the cutting operation when the front knife is moving rearwardly.

Having thus described my invention it will be seen that changes and modifications may be made therein by those skilled in the art without departing from the spirit and scope of the invention and I do not wish to be limited to the details herein disclosed, but what I claim is:

1. In pile tuft cutting mechanism for an Axminster loom to weave a fabric connected at its fell to rearwardly extending warp threads, a cloth board to support the fabric, spaced teeth extending rearwardly from the cloth board and having portions thereof located under the cloth and other portions projecting rearwardly behind the fell of the cloth, the loom operating with a tube frame from which project tuft forming yarns incorporated into the fabric at the fell thereof and to be cut from the tube frame, hooks projecting upwardly from said teeth behind the fell of the cloth and extending along and having supporting relation with respect to the tufts to be cut, a back knife located behind the tufts to be cut and having a front cutting edge, means to move the back knife forwardly and maintain the same stationary during the cutting operation with the cutting edge thereof closely adjacent to the rear portions of the tufts to be cut, a second knife in front of the tufts having a rear cutting edge, means to move the second knife rearwardly under the back knife while the latter is stationary to cause cooperation between the cutting edges to sever the tufts from the tube frame and move the cutting edge of the front knife to a position behind the cutting edge of the back knife, said hooks supporting the tufts against a rearwardly directed force exerted by the front knife during the cutting operation, said second named means thereafter moving the front knife forwardly to a position in which the cutting edge thereof is in advance of the fell of the cloth to the end that lint collecting on the top of the front knife incidental to the cutting operation may fall off said front knife and be deposited on the fabric in locations in front of those portions of the teeth which project rearwardly behind the fell of the cloth.

2. In pile tuft cutting mechanism for an Axminster loom to weave a fabric connected at its fell to rearwardly extending warp threads, a cloth board to support the fabric, spaced teeth extending rearwardly from the cloth board and having portions thereof located under the cloth and other portions projecting rearwardly behind the fell of the cloth, the loom operating with a

tube frame from which project tuft forming yarns incorporated into the fabric at the fell thereof and to be cut from the tube frame, hooks projecting upwardly from said teeth behind the fell of the cloth and extending along and having supporting relation with respect to the tufts to be cut, a back knife having a front cutting edge, means to move the back knife forwardly and then maintain said knife stationary during the cutting operation with the cutting edge thereof closely adjacent to the rear portions of the tufts and over said hooks, a front knife in front of said tufts having a rear cutting edge, means to move the front knife rearwardly under the stationary top knife to cause cooperation between the cutting edges of said knives to sever the tufts from the tube frame, said hooks supporting the tufts against a rearwardly directed force exerted by the front knife during the cutting operation, said second named means also operative to move the cutting edge of the front knife to a position behind the fell of the cloth to move lint falling on the top knife incidental to the cutting operation to be located on said front knife in advance of the cutting edge thereof, said second named means thereafter moving the front knife forwardly to a position in which the cutting edge thereof is in advance of the fell of the cloth whereby lint falling from the front knife when the latter is in forward position will be deposited on the fabric being woven in front of those portions of the teeth of the nose board which project rearwardly behind the fell of the cloth.

3. In tuft cutting mechanism for an Axminster loom weaving a fabric connected at its fell to rearwardly extending warp threads, the loom having a fabric supporting cloth board from which project rearwardly teeth extending behind the fell of the fabric and the loom also operating with a tube frame from which extend tuft yarns which project downwardly and rearwardly and then upwardly to form tufts to be cut from the yarns of the tube frame, a back cutting knife behind the tuft yarns having a front cutting edge, means to move the back knife forwardly and maintain the same stationary in a position with the cutting edge thereof closely adjacent to and behind the tuft yarns, upwardly projecting hooks formed on said teeth extending along and closely adjacent to the rear portions of the tufts under the cutting edge of the back knife when the latter is held stationary in cutting position by said means, a front knife in front of the tuft yarns having a rear cutting edge, and means to move the front knife rearwardly under the stationary back knife to cause cooperation between said cutting edges to sever the tufts from the yarns of the tube frame and also move the cutting edge of the front knife to a position behind the cutting edge of the stationary back knife to force lint on the top of said front knife to a position in front of the cutting edge of said front knife, said upwardly projecting hooks supporting the rear portions of the tufts during backward motion of the front knife during the cutting operation, said second named means thereafter moving the front knife forwardly to a position with the cutting edge thereof in advance of the fell of the cloth, whereby lint falling from the top of the front knife when the latter is in forward position will be deposited on the fabric in front of those portions of the teeth of the cloth board which project behind the fell of the cloth.

4. In tuft cutting mechanism for an Axminster

loom weaving a fabric connected at its fell to rearwardly extending warp threads, the loom having a fabric supporting cloth board from which project rearwardly teeth extending behind the fell of the fabric and the loom also operating with a tube frame from which extend tuft yarns which project downwardly and rearwardly and then upwardly to form tufts to be cut from the yarns of the tube frame, upwardly projecting hooks on said teeth located behind the fell of the cloth, the free ends of the tuft forming yarns projecting from the tube frames moving up the rear surfaces of said teeth and over said hooks to positions in front of the latter, said hooks thereafter extending upwardly along the rear portions of said free ends of the tuft forming yarns to support said free ends, a back knife having a front cutting edge, means to move the back knife forwardly and maintain the same in stationary position with the cutting edge thereof behind and closely adjacent to the tuft yarns and over said hooks, a front knife in front of said tuft yarns having a rear cutting edge, means to move the front knife rearwardly and under the stationary back knife to cause cooperation between the said cutting edges to sever the yarns projecting from the tube frame, said hooks supporting the tufts against a rearwardly directed force exerted by the front knife during the cutting operation, said second means operative to move the cutting edge of the front knife to a position behind the front edge of the back knife during the cutting operation to move lint on the top of the front knife to a position in front of the cutting edge thereof, said second named means thereafter moving the front knife forwardly to a position in which the cutting edge of said front knife is in front of the fell of the cloth, whereupon lint falling from the front knife when the latter is in forward position is deposited on the fabric in front of those parts of the teeth of the cloth board which project behind the fell of the cloth.

5. In tuft cutting mechanism for an Axminster

loom weaving a fabric connected at its fell to rearwardly extending warp threads, the loom having a fabric supporting cloth board from which project rearwardly teeth extending behind the fell of the fabric and the loom also operating with a tube frame from which extend tuft yarns which project downwardly and rearwardly and then upwardly to form tufts to be cut from the yarns of the tube frame, upwardly projecting hooks on said teeth located behind the fell of the cloth, the free ends of the tuft forming yarns projecting from the tube frames moving up the rear surfaces of said teeth and over said hooks to positions in front of the latter, said hooks thereafter extending upwardly along the rear portions of said free ends of the tuft forming yarns, a back knife having a front cutting edge, means to move the back knife forwardly and maintain the same in stationary cutting position with the cutting edge thereof over said hooks, a front knife in advance of the tuft yarns having a rear cutting edge, and means to move the front knife rearwardly to a position under the stationary back knife to cause cooperation between said cutting edges to sever the tufts from the yarns of the tube frame, said second named means effective also to move the cutting edge of the front knife to a position behind the cutting edge of the stationary back knife, said hooks extending along and supporting the rear free ends of the yarns projecting from the tube frame and tending to resist backward motion thereof during rearward motion of the front knife, said second named means thereafter moving the front knife forwardly to a normal position with the rear cutting edge thereof in advance of said hooks whereby any lint which accumulated on top of the front knife during the cutting operation may be deposited on the fabric in front of said hooks and those portions of the teeth of the cloth board which project behind the fell of the fabric.

EDWARD J. DACEY.
